UNITED STATES PATENT OFFICE.

PARKE E. SHEE, OF LANCASTER, PENNSYLVANIA, ASSIGNOR OF ONE-HALF TO
EDWARD I. NOBLE, OF LANCASTER, PENNSYLVANIA.

GARMENT HANGER.

Application filed March 31, 1922. Serial No. 548,407.

To all whom it may concern:

Be it known that PARKE E. SHEE, a citizen of the United States, residing at Lancaster, in the county of Lancaster and State 5 of Pennsylvania, has invented new and useful Improvements in Garment Hangers, of which the following is a specification.

The present development relates to garment hangers, and is intended for use with 10 garments of various sorts, although it is herein shown and described in connection with trousers.

It has for its object to provide a readily 15 constructed hanger which will serve not only to support the garment, but also will impose upon it a transverse stretching action, which, in the case of trousers, as well as other garments, when this is desirable, will keep them, when they are supported by 20 it, in stretched condition so as to maintain them unwrinkled and preserve a straight neat appearance. The construction is such that a garment is positively gripped, and the parts of the hanger do not enter between 25 the layers or plies of the garment to distend it, but the layers will be held always in close position and their smooth unwrinkled condition preserved.

In the drawings herewith, I have shown 30 one embodiment of my invention, and in said drawings:

Fig. 1 is a view in side elevation of a 35 garment hanger constructed in accordance with my invention, a portion of a pair of trousers being shown engaged by the hanger.

Fig. 2 is a vertical sectional view between the gripping members of the clasp.

Fig. 3 is a sectional view on the line 3—3 40 of Fig. 2.

Fig. 4 is a detail view to show the spring abutments adjacent the loop of the hanger bar.

Fig. 5 is a sectional view of the clasp in 45 engagement with the garment taken on the line 5—5, Figure 1.

Referring to the drawings by numbers, like numbers indicating like parts in the 50 several views, 10 denotes the body or bar member of the hanger, formed of a single piece of material centrally bent and having its portions on opposite sides of the bend crossing and extending in opposite directions to form a closed integral loop 11. The

bar 10 will be made of wire or rod of proper 55 gauge and temper to carry the load.

At each end of the bar are slidingly mounted the clips or clasps 12, made of two similar members having the gripping jaws 13 and riveted together, preferably by the 60 hollow rivet members 14, a spring 15 being provided which tends normally to urge the members into the closed position shown in full lines in Fig. 3.

It will be seen from Figs. 1 and 2 that 65 the bar passes through the rivet members 14 and the spring 15 so that the clasps 12 have a free sliding movement on the bar 10, the end 16 of the bar being upset in any suitable manner so as to prevent the clasps 12 70 from slipping off the bar.

The clasps 12 have free sliding movement on the bar 10, as will be apparent from Fig. 1, so that they may be adjusted from the extreme positions shown in dotted lines 75 in Fig. 1 nearer the central loop 11, and provide adjustment for different widths of garments. It will be noted that the rivets afford bearings for the clasps 12 during the pivotal movement of the jaw members, and additionally, function as bushings which 80 permit free sliding movement of the clips along the bars.

The clasps 12 are normally urged to their 85 extreme positions on the bar 10 by means of the springs 17 which are of sufficient length and resiliency to give considerable endwise thrust to the clasps 12, and, when they are engaged with a garment, as shown in Fig. 1, exert a sufficient pull on the garment to maintain it in properly stretched condition. At their inner ends, the springs 90 17 take their bearings against abutments 18, which abutments, as shown in Fig. 4, are

preferably formed by slipping small sleeves 95 over the ends of the rod before they are upset at 16 into close relation to the loop, and, if desired, securing them by soldering or other suitable manner. These sleeves form abutments for the springs 17 so as to prevent the springs from working into and about the loops 11, which would reduce to a very considerable extent their tension and the usefulness of the device.

The clasps or clips 12 will be made of 105 proper size, and their springs 15 of sufficient strength so that the jaws 13 will positively grip and sustain the load and exert the

transverse stretching pull upon the garment under the action of the springs 17, without danger of the springs 17 forcing the clasps 12 out of engagement with the garment. 5 Preferably, when used for suspending trousers, as shown and described in the present example of the use of the device, the clasps will be engaged with the trousers as shown, by gripping the inner plies of the legs of the 10 trousers at the extreme edges so as to exert a proper stretching action, and yet leave no marks or indentations from the jaws 13 on the exterior surface of the garment.

In order that the garment may be suspended on a hanger pole or other type, there 15 is connected with the loop 11 the hook 19 having a loop-engaging eye; a shank member, and the large open hook portion, so that it will take readily over the hanger pole of a 20 clothes cabinet or closet.

It will be observed that the construction is such as to provide a hanger which will effectively support and stretch the clothes, and that such hanger is of very narrow 25 width, so that a large number of hangers may be used upon a single support, and a maximum number of garments hung. As appears from Fig. 3, the width of the top of the 30 hanger, all of the other parts lying entirely within the transverse area of the clasps 12. Furthermore, the device may be very readily and cheaply constructed and assembled be-

cause of its simplicity, and derangement or breakage of the parts are unlikely.

35

I claim:

1. A garment hanger comprising an integral bar member centrally bent and having its portions on opposite sides of the bend crossing and extending in opposite directions to form a closed loop, a supporting hook loosely engaging said loop, clasps each formed of a pair of spring jaws, rivets holding together said jaws and serving as bearings therefor, said bar passing through the rivets, springs on said bar tending to move the clasps outwardly toward the ends of the bar, the bar having upset ends to limit the movement of the clasps and abutment means on said bar adjacent said loop for the inner ends of said spring. 45

2. A garment hanger comprising an integral bar member, a supporting hook loosely connected to said bar centrally thereof, spring clasps slidably mounted on the bar on opposite sides of said hook, each clasp comprising a pair of jaws, rivets holding together said jaws and serving as bearings therefor, said bar passing through the rivets whereby the latter serve as bushings to facilitate the sliding movement of the clasps, and springs urging said clasps toward the ends of said bar, the bar having upset ends. 55 60

In testimony whereof I have hereunto set my hand.

PARKE E. SHEE.
